UNITED STATES PATENT OFFICE.

EDWARD A. HOLRITZ, OF ST. PAUL, MINNESOTA, ASSIGNOR OF ONE-HALF
TO JAMES C. BRAMWELL, OF ST. PAUL, MINNESOTA.

COPY-HOLDER FOR TYPE-WRITERS.

SPECIFICATION forming part of Letters Patent No. 708,554, dated September 9, 1902.

Application filed February 24, 1902. Serial No. 95,181. (No model.)

To all whom it may concern:

Be it known that I, EDWARD A. HOLRITZ, a citizen of the United States, residing at St. Paul, in the county of Ramsey and State of Minnesota, have invented certain new and useful Improvements in Copy-Holders for Type-Writers, of which the following is a specification.

My invention relates to improvements in copy-holders designed to be attached to type-writers, its object being to provide a holder that will hold the copy in front of the operator and which when not in use may be collapsed and folded behind the machine without being in the way of the type-writer cover.

To this end my invention consists in the features of construction and combination hereinafter described and claimed.

In the accompanying drawings, forming part of this specification, Figure 1 is a front elevation of my improved copy-holder. Fig. 2 is a side elevation partly broken away. Fig. 3 is a rear elevation partly broken away. Fig. 4 is a rear view showing the parts in collapsed position. Fig. 5 is a detail of a slideable collar forming part of my invention, and Fig. 6 is a section on line xx of Fig. 2 looking down.

In the drawings, 2 represents a vertical standard supported by a clamp 3. The clamp 3 is provided with downwardly-projecting lugs 4 and 5, a thumb-screw 6 being threaded through the lug 4, by means of which the clamp is fastened to the bottom of the rear of the type-writer.

Slidable upon the standard 2 is a collar 7, carrying the arm 8. The arm 8 is doubled upon itself and carries at its upper end a post 9.

In order to hold the collar 7 with its connected parts supported at the top of the standard 2, I provide a pin 10, projecting outwardly from the upper end of the standard. Formed in one side of the collar 7 is the downwardly and horizontally running slot 11. By turning the collar so that the pin 10 is brought to the inner end of the horizontal portion of the slot 11 the parts will be held in raised position, as illustrated in Fig. 3. The collar 7 also carries a downwardly-projecting pin 12, adapted to project into an opening 13 in

the clamp 3 to hold the arm 8 in the position shown in Fig. 4.

The post 9, carried by the upper end of the arm 8, fits within a sleeve 14, the arm 8 passing through a vertical slot 15 in said sleeve. The slot 15 is formed at its lower end with an offset portion 16, so formed as to leave an intermediate downwardly-projecting shoulder 17. By carrying the arm 8 underneath the shoulder 17 the upper portion of the copy-holder will be supported in the position shown in Figs. 1 to 3.

Carried by the sleeve 14 is a cross-piece 18, connected by lazy-tongs with an upper cross-piece 19. The bars 20 of the lazy-tongs are provided with pivots 21, passing through slots 22 in the cross-piece 18, and the upper bars 23 of the lazy-tongs are provided with pivots 24, passing through slots 25 in the upper cross-piece. In order to hold the lazy-tongs in extended position, I provide catches 26, having pivotal support 27 in the ends of the lower cross-bar and adapted to be turned downward against the pivots 21. A rod 28 is secured in the sides of the upper cross-bar 19 and is provided with a spring 29, by which it is held against the paper.

In use the clamp 3 is secured to the bottom of the framework at the rear of the machine, so as to stand behind the carriage, or, if desired, a construction of clamp may be used by which it may be secured to the table edge or other support in the rear of the machine. The arm 8 is then lifted and by means of the pin 10 is supported in the position shown in Fig. 1. The copy-holding frame is then lifted and turned to bring the arm 8 underneath the shoulder 17, and the lazy-tongs are then extended and held in extended position by means of the catches 26, as shown in Fig. 1. When it is desired to collapse the holder, the catches 26 are first released to allow the cross-bars 18 and 19 of the copy-holding frame to be brought together. The collapsed copy-holding frame is then turned to bring the arm 8 into the vertical slot 15. The collar 7 is then released from the pin 10 and allowed to drop on the standard 2, as shown in Fig. 3, the parts then being held from turning upon the standard by the pin 12, carried by the collar 7 and projecting into the opening

13 in the clamp. In this position of the parts the arm 8 is held parallel with the rear of the machine and the collapsed copy-holding frame is held parallel with the arm 8, so that the parts are out of the way of the type-writer cover.

It will be evident that the construction and combination may be more or less modified without departing from my invention, the scope of which is defined in the following claims.

I claim—

1. In a copy-holder of the class described, the combination of a vertical standard, a collar slidable upon said standard, an interlocking connection between said collar and the upper end of said standard, an upwardly-projecting arm carried by said collar said arm being bent to bring its upper end toward said standard, a copy-holding frame having rotatable support upon the upper end of said bent arm, means for holding said copy-holding frame and said bent arm in parallel planes, and means for holding said frame at an angle with said arm.
2. In a copy-holder of the class described, the combination of a vertical standard provided with means for attachment to a support, a collar slidable upon said standard, an upwardly-projecting arm carried by said collar, said arm being bent to bring its upper end toward the standard, means for supporting said collar at the upper end of said standard, a collapsible copy-holding frame rotatably supported upon the upper end of said arm, means for securing said frame in a plane at right angles with the plane of said bent arm, and means for securing said frame parallel to said bent arm.
3. In a copy-holder of the class described, the combination of a vertical standard and a supporting-clamp therefor, a collar slidable upon said standard, an arm carried by said col-

lar, means for holding said collar supported at the upper end of said standard, a post carried by the upper end of said arm, a sleeve inclosing said post, and a collapsible copy-holding frame carried by said sleeve.

4. In a copy-holder of the class described, the combination of a standard, a supporting-clamp therefor, a collar slideable upon said standard and provided with a downwardly and horizontally disposed slot in its side, an outwardly-projecting pin carried by the upper end of said standard and adapted to fit into said slot to support said collar, an arm carried by said collar, and a collapsible copy-holding frame rotatably mounted upon the upper end of said arm.

5. In a copy-holder of the class described, the combination of a standard and supporting-base therefor, a collar slideable upon said standard, an interlocking connection between said collar and base, an interlocking connection between said collar and the upper end of said standard, a bent arm supported by said collar, and a collapsible copy-holding frame carried by the upper end of said arm.

6. In a holder of the class described, the combination of a standard, a supporting-base therefor, a collar slideable upon said standard, an interlocking connection between said collar and the upper end of said standard, a bent arm supported by said collar, a post carried by the upper end of said arm, a sleeve inclosing said post and provided with a slot to receive said arm and to hold said sleeve in adjusted positions upon said post, and a collapsible copy-holding frame carried by said sleeve.

In testimony whereof I affix my signature in presence of two witnesses.

EDWARD A. HOLRITZ.
